TRAFFIC SIGNAL

Michael J. Downey, San Francisco, Calif.

Application June 25, 1951, Serial No. 233,420

3 Claims. (Cl. 116—63)

1

My invention relates to signals for the direction of motorists; and one of the objects is the provision of such a signal that may be displayed by raising it above the grade or street level, or hidden by lowering it below the street level as control of traffic conditions make desirable.

Another object of the invention is to provide a signal of the character described which may be locked in place whether in displayed or concealed position.

The invention possesses other objects, some of which with the foregoing will be brought out in the following description of the invention. I do not limit myself to the showing made by the said description and the drawings, since I may adopt variant forms of the invention within the scope of the appended claims.

Referring to the drawings: Fig. 1 is an elevation of my traffic signal when in displayed position, a portion of the housing being in vertical section. Fig. 2 is an elevation of my traffic signal with the signal post and sign and base reversed to concealed position. The housing is shown in central vertical section and part of the signal base is also shown in section to disclose the locking means. Fig. 3 is a plan view of the signal when in concealed position, a portion being shown in section to disclose the lock.

Fig. 4 is an elevation of a variant form of my signal, together with hydraulic operating means therefor. Parts are shown in section, the better to reveal the structure.

In the control of city traffic, it is frequently necessary to display signs for the direction of motorists during rush hours or during parades, and then withdraw such signs after this temporary use is past.

According to my observation, this has generally been accomplished by the use of a signal post set in a broad heavy base, and which is kept during periods of non-use on the sidewalk and wheeled or carried out to location when needed by the traffic control officer.

Quite obviously, this is a make-shift arrangement and objectionable for that reason, but an even stronger objection lies in the attractiveness which unattached objects of this sort have for exuberant youth, especially in college towns.

My invention meets the requirements of this situation by the provision of a housing set below the level of the pavement at the point where the signal is to be used; and arranging the parts of the signal and the housing so that the signal can be displayed above the housing or concealed therein, and in both arrangements locked in place,

10

In more detail, my traffic signal comprises a housing 1, including a length of cylindrical steel pipe 2, threaded at both ends, and having a cap 3, threaded on the lower end. The cap has a drain hole 4 therethrough for the escape of any water that may collect in the housing. At the upper end, the pipe is threaded into the head 6, which forms a bell on the pipe, and is set flush with the pavement 7 as shown, at whatever location it is anticipated that a temporary and movable traffic signal will be needed.

15

Fitting easily into the bell, is the base 8, which carries the signal post 9 and signal plate 12 on which the indicia 13, comprising the traffic directions are displayed. The base 8 fits the bell either face up, and the post and plate are of such size that they fit within the pipe 2, so that the base with post extending upwardly may be nested in the bell to display the signal, or nested in the bell with the post extending downwardly into the chamber formed by the pipe, to conceal the signal.

20

In either position, means are provided for locking the base in the bell. Preferably the base is cast metal; and cored in one side midway between the flat faces, is a recess 16, generally circular as seen in Fig. 3, but having the stop lugs 17 and 18 spaced in the curved wall, about as shown.

25

Fixed rigidly on the short shaft 19, journaled in the base on each side of the recess is a locking disk 21 corresponding to a lock bolt, and having oppositely arranged extensions or lugs 22 and 23 as shown. Conveniently the parts are assembled by first inserting the disk into the recess and then forcing the properly dimensioned shaft into place, the shaft ends turning easily in the base but having a force fit in the disk.

30

With the lug 23 against the stop 17, no part of the locking disk extends beyond the curved side of the base, which may then be freely inserted or withdrawn from the bell. With the lug 23 against the stop 18, the lug 22 extends out from the curved face and into the groove 24 formed all around the inside of the bell, so that the bolt will engage in the groove in any position in which the base is placed in the bell with the post extending up or down.

35

The end faces of the shaft 19 are provided with spaced holes 26, fitting a two-prong key carried by the traffic officer on duty. The bottom face of the base is cored out to provide a grip 27 by which the inverted base may be lifted out of the housing.

40

Since streets do not always intersect at regular angles, means are provided for fixing the position

2

45

50

55

of the base about a vertical axis. This is done by forming a series of vertical grooves 28 in the inside face of the bell, and an interlocking bead 29 on the face of the base. The spacing is such as to meet the conditions of any likely intersection of city streets.

Thus my signal may be displayed during the period of need, and thereafter inverted and concealed at the same location, without creating any traffic hazard. In either setting, my signal is locked in place and reasonably secure against casual and juvenile mischief.

In some places it may be desirable to direct traffic or convey information to motorists by remote control. For example, in a garage which has exhausted its storage facilities, it may be desired to display a "Full" sign at the entrance before other cars can block the driveway.

In Fig. 4, I have shown an installation particularly intended for such use, that is, for operation of a signal by remote control. A hydraulic cylinder 30 is connected to and arranged below the head or bell 31 set flush in the floor or pavement 32 at the desired location. In the bottom of the bell, a packing gland 33 seals the piston rod 34. The rod forms a signal post and carries an inverted cup 36 on its upper end. The cup bears the desired indicia 37, such as the word "Full," repeated several times about its cylindrical face, so that the sign may be read from any approach.

Fixed on the rod within the cylinder is a piston 38, and pipes 39 and 41 connect opposite ends of the cylinder to the hydraulic fluid supply cylinder 42, so that an alternate flow of fluid to the ends of cylinder 30 raises and lowers the sign as the case may be.

Disposed in the cylinder 42 is a piston 43, on rod 44, fixed in the cross head 46, arranged to slide back and forth in the guide bars 47. The cross head is connected by link 48 to the crank arm 49, fixed on the same shaft with a disk 51, and driven by the reduction gear motor 52 at about 4 R. P. M. Diametrically opposite cam points 53 are arranged on the disk to open the switch 54 twice with each revolution of the disk and crank arm, the points of operation being at a time when the piston 43 is at an end of its cylinder.

The switch 54 is arranged in the motor circuit 56-57, and is normally closed. A line 58 with then normally open push button switch 59 bypasses or shorts across the switch 54. Thus between strokes, the piston 43 is always at one end or the other of the cylinder 42, with the signal 36 on display in its upper position or the cup 36 nested flush in the bell 31. When it is desired to raise the signal from its hidden position, or lower it from the position of display, the push button switch 59 is depressed and held for a few seconds

to start the motor and carry the cam 53 past the contact arm of the switch 54 so that switch 54 closes. The motor then operates to move the piston 43 through its stroke, until the other cam opens the switch at the end of the stroke. It is obvious that the hydraulic fluid in the cylinder 30 locks the post and indicia bearing means in both displayed and concealed positions.

The stroke of the piston 43 is of course twice the throw of the crank 49; and the volume of hydraulic fluid displaced by each stroke of the piston is the volumetric capacity of the corresponding side of the piston 38. In order to avoid an excessive length of the cylinder 42, it is proportionately of greater diameter and shorter length than the cylinder 30, so that the signal may be lifted to a preferred height of thirty to thirty-six inches with only a short throw of the crank and a corresponding short length of cylinder 42. The system is conveniently filled with hydraulic fluid through the capped fittings 61 and 62, and drained through the cock 63.

I claim:

1. A traffic signal comprising a housing including a belled head at its upper end, a base loosely fitting in the belled head in upright and upside down position, a post fixed in the base and in the upside down position extending to adjacent the bottom of the housing, and a sign carried by the post.

2. A traffic signal comprising a housing including a belled head at its upper end, a base loosely fitting in the belled head in upright and upside down position, a post fixed in the base and in the upside down position extending to adjacent the bottom of the housing, a sign carried by the post, and means for locking the base in the belled head in either position.

3. A traffic signal comprising a housing including a belled head at its upper end, a base loosely fitting in the belled head in upright and upside down position, a post fixed in the base and in the upside down position extending to adjacent the bottom of the housing, a sign carried by the post, and interlocking means between the base and the belled head for fixing their relative positions in a vertical axis.

MICHAEL J. DOWNEY.
